CLAIM

The ornamental design for a telephone set, as shown and described.

DESCRIPTION

FIG. 1 is a front, top and right side perspective view of a telephone set showing our new design in cradled relationship;

FIG. 2 is a similar perspective view thereof with the handset raised above the base;

FIG. 3 is a top plan view of the headset and base as shown in FIG. 2;

FIG. 4 is a front elevational view thereof as shown in FIG. 2;

FIGS. 5 and 6 are respectively right and left side elevational views thereof;

FIG. 7 is a rear elevational view thereof as shown in FIG. 4;

FIG. 8 is a bottom plan view of the handset and base as shown in FIG. 3;

FIGS. 9, 10 and 11 are respectively second, third and fourth embodiments thereof, the sole differences being the keyboard button arrangements and side elevational views corresponding to button placements.
